H. A. DOUGLAS.
ELECTRICAL CONDUCTOR.
APPLICATION FILED FEB. 4, 1918.

1,339,694.

Patented May 11, 1920.

19 Inventor:
17 Harry A. Douglas.
By G. H. Gragg Atty.

UNITED STATES PATENT OFFICE.

HARRY A. DOUGLAS, OF BRONSON, MICHIGAN.

ELECTRICAL CONDUCTOR.

1,339,694.

Specification of Letters Patent.

Patented May 11, 1920.

Application filed February 4, 1918. Serial No. 215,331.

To all whom it may concern:

Be it known that I, HARRY A. DOUGLAS, citizen of the United States, residing at Bronson, in the county of Branch and State 5 of Michigan, have invented a certain new and useful Improvement in Electrical Conductors, of which the following is a full, clear, concise, and exact description.

My invention relates to so-called electrical 10 conductors and has for its object the provision of an improved terminal construction for current conducting wire.

In practising my invention I employ two 15 elements, one in the form of a sleeve and the other in the form of a collar surrounding the sleeve, this collar having a wire engaging end wall, and wire passing through the bore of the sleeve and having an end portion returned upon the exterior of the 20 sleeve to form a bight in the wire at one end of the sleeve, there being space between lateral portions of the collar and sleeve for receiving said end portion of the wire, said bight being engaged by the aforesaid end 25 wall of the collar to maintain the bight in the wire in firm engagement with said sleeve and collar.

In the preferred embodiment of the invention the sleeve is exteriorly threaded and 30 the collar is in the form of a nut threaded upon the sleeve. The returned end of the wire is desirably received in an external recess upon the lateral portion of the sleeve. The construction which I have devised is of 35 particular service where the conducting wire is subdivided into fine strands, commonly called tinsel. Where the wire is thus subdivided into strands the conductor is in the nature of a so-called electrical cord that is 40 highly flexible in order that the conductor may be freely manipulated and adapted to varying environments.

An electrical conductor having flexible 45 strands and constructed in accordance with my invention is of use in including lamp receiving sockets in circuit, establishing circuit relation of the electrical connectors, and in wire plugs, though it will be obvious that the invention is not to be limited to these 50 particular purposes.

I will explain my invention more fully by reference to the accompanying drawing showing the preferred embodiment thereof and in which Figure 1 is a view, partially

in section and partially in elevation, illustrating a socket wired by the device of my invention; Fig. 2 is a longitudinal sectional view of an electrical conductor and terminal elements pertaining thereto constructed and assembled in accordance with the invention, this figure being a detail that illustrates the lateral plug at the left hand end of the structure shown in Fig. 1; Fig. 3 is a sectional view on line 3-3 of Fig. 2; Fig. 4 illustrates a connector having a plug 65 wired by the device of my invention; Fig. 5 is a view on line 5-5 of Fig. 4; Fig. 6 is a longitudinal sectional view of the electrical conductor and terminal elements pertaining thereto that are employed in the 70 structure of Fig. 4; Fig. 7 illustrates a form of socket having a removable plug which is wired by my improved conductor; Fig. 8 is a view on line 8-8 of Fig. 7; and Fig. 9 is a longitudinal sectional view of the 75 electrical conductor and terminal elements pertaining thereto that are employed in the structure of Fig. 7.

Like parts are indicated by similar characters of reference throughout the different 80 figures.

Reference will first be made to the construction shown in Figs. 1, 2 and 3 which illustrate the adaptation of my invention to a lamp socket that includes a metallic shell 85 1 in one end of which is permanently secured a plug 2 of insulation. The other end of this shell is formed with bayonet slots 3 adapted to receive the bayonet pins 4 upon the base of an incandescent lamp 5. The 90 structure illustrated is a so-called single pole structure in which one terminal of the lamp filament 6 is connected with a metallic sheath 7 that surrounds parts of the lamp and has electrical engagement with the metallic shell 1 that is suitably connected with 95 one terminal of a source of current. The other terminal of the filament 6 is in the nature of a button 8 which is engaged by the contact plunger 9 that is pressed forwardly 100 by a coiled spring 10. This coiled spring presses another contact plunger 11 rearwardly. These contact plungers project through the ends of a metallic spring barrel 12 that serves to include the contact plungers in circuit. The plug 2 has a lateral opening which receives the electrical conductor of my invention. As illustrated, this 105

conductor is also in the nature of a plug having a contacting element 13 connected with the other terminal of the aforesaid source of current and which is provided 5 with a peripheral groove 14 to receive the hemispherical rear end of the contact plunger 11 to complete the circuit of the lamp filament 6 when such circuit is elsewhere established. The contacting element 13 is 10 in the nature of a nut or collar and this collar is preferably in the form of a metallic nut having a threaded bore and formed with a wire engaging end wall 15 which preferably, though not necessarily, closes 15 one end of the bore of the nut. Wire 16, by means of which the contact element 13 is connected with the source of current, is preferably subdivided into a number of strands in order that it may be flexible to a high degree to constitute a so-called "conducting cord." This wire passes through a metallic sleeve 17 which is threaded upon its exterior so that the nut 13 may be screwed thereupon. The sleeve 17 has an enlargement or extension 17¹ to receive the serving 20 or insulation 18 that covers the wire 16, this serving being desirably absent where the wire passes through the threaded sleeve or sleeve section. The wire 16 passes through 25 the bore of the sleeve 17 and has an end portion 16¹ which is returned upon the exterior of the sleeve 17 to form a bight 16² in the wire 16 at the outer end of the sleeve 17. The space between lateral portions of the 30 nut 13 and the sleeve 17 that receives the wire end 16¹ is desirably provided by forming an external recess 19 in the sleeve 17 that is of a size snugly to receive the wire end 16¹. The bight 16² in the wire 16 is engaged by the end wall 15 of the nut 13 to 35 maintain this bight in firm engagement with the nut 13 and sleeve 17.

The connector shown in Figs. 4 and 5 is a so-called single pole connector that receives 40 a lamp which is similar to the lamp shown in Fig. 1, like parts of the two lamps being given similar characters of reference.

The shell 1¹ has bayonet slots 3¹ for receiving the bayonet pins 4 projecting from 45 the base of the lamp. The plug 2¹ is received in the intermediate portion of the shell and supports two oppositely sprung 50 pressed plunger contacts 9¹, 11¹, the plunger contact 9¹ being engageable with the lamp base contact 8 while the plunger contact 11¹ is engageable with the end of another form 55 of metallic nut 13¹ instead of with a side of such a nut that is the case with the construction shown in Fig. 1. This nut 13¹ is 60 assembled with the split halves of an insulating core 20 which has a bore extending therethrough that receives the conductor structure that includes the nut 13¹ in circuit connection. With the exception of the nut, 65 this conductor structure (detailed in Fig.

6) is similar to the structure shown in Fig. 2 and similar parts are given similar characters of reference.

It will be noted that the plug 20 carries bayonet pins 21 by which it may be removably inserted within bayonet slots 22 in the rear end of the shell 1¹. In the structure illustrated in Fig. 7 the plug 20, provided with bayonet pins 21, is removably received within the bayonet slots 22 in the rear end 70 of a shell 1² whose forward end is provided with bayonet slots 3² receiving a lamp similar to the lamps shown in Figs. 1 and 4, similar parts of the lamps having similar characters of reference. 80

The plug 20¹ carries a spring barrel 23 that houses a spring 24 which presses a plunger contact 25 forwardly into engagement with the lamp contact 8. The rear end of the spring barrel 23 is formed to constitute a threaded nut 13² that performs the assembling function of the nuts shown in Figs. 2 and 6. The nut 13² is complementary to parts which are similar to the parts complementary to the nuts 13, 13¹ shown in Figs. 2 and 6, all of these complementary parts being given similar characters of reference. 90

In the form of the invention shown in Figs. 2 and 6 the nuts are provided with screwdriver slots 26 in order that they may 95 be screwed home. In the form of the invention shown in Fig. 9 the spring barrel 23 may be gripped in order to turn the nut 13² home.

In all cases there should preferably be 100 sufficient clearance between the nuts and the extensions 17¹ of the sleeve 17 to permit the nuts firmly to press the bights 16² of the wire 16 without having the nuts bottom against the sleeve portions 17¹. By the construction specified not only is firm electrical 105 engagement effected and maintained between the sleeve 17 and the nut 13 but with withdrawal of the wire 16 from the sleeve 17 is positively prevented owing to the presence 110 of the bight 16², the formation of this bight being made possible by the provision of the external lateral recess 19 in the sleeve 17. This lateral recess is in the zone of the threads upon the sleeve 17 and in the zone 115 of the threaded portion of the nut that engages the threads upon the sleeves.

While I have herein shown and particularly described the preferred embodiment of my invention I do not wish to be limited to 120 the precise details of construction shown as changes may readily be made without departing from the spirit of my invention, but having thus described my invention I claim as new and desire to secure by Letters Pat- 125 ent the following:

1. An electrical conductor including two elements, one in the form of an exteriorly threaded sleeve and the other in the form of a nut upon the threaded sleeve, this nut hav- 130

- ing a wire engaging end wall; and wire passing through the bore of the sleeve and having an end portion returned upon the exterior of the sleeve to form a bight in the wire at one end of the sleeve, there being an external recess upon a lateral portion of the sleeve and in the zone of the threads on the sleeve and in the zone of the threaded portion of the nut that engages the threads upon the sleeve, said recess receiving said end portion of the wire, said bight being engaged by the aforesaid end wall of the nut to maintain the bight in the wire in firm engagement with said sleeve and nut.
- 5 10 15 20 25 30
2. An electrical conductor including two elements, one in the form of an exteriorly threaded sleeve and the other in the form of a nut upon the threaded sleeve, this nut
- having a wire engaging end wall; and wire passing through the bore of the sleeve and having an end portion returned upon the exterior of the sleeve to form a bight in the wire at one end of the sleeve, there being an external recess upon a lateral portion of the sleeve and in the zone of the threads on the sleeve and in the zone of the threaded portion of the nut that engages the threads upon the sleeve, said recess receiving said end portion of the wire which is confined in said recess by engagement with the inner side of the nut.

In witness whereof, I hereunto subscribe my name this thirtieth day of January A. D., 1918.

HARRY A. DOUGLAS.
